UNITED STATES PATENT OFFICE.

JAMES A. LOYSTER, OF CAZENOVIA, NEW YORK.

DOOR OPERATING AND LOCKING MECHANISM FOR JAILS.

1,136,351.

Specification of Letters Patent. Patented Apr. 20, 1915.

Application filed October 20, 1910. Serial No. 588,028.

To all whom it may concern:

Be it known that I, JAMES A. LOYSTER, of Cazenovia, in the county of Madison, in the State of New York, have invented new and useful Improvements in Door Operating and Locking Mechanisms for Jails, of which the following, taken in connection with the accompanying drawings, is a full, clear, and exact description.

10 This invention relates to certain improvements in door operating and locking mechanisms for jails and similar places in which a series of cells are usually arranged side by side and provided with separately movable doors opening upon a corridor or exercising space which is also provided with a separate door located at one end of the corridor or series of cells.

In the construction of modern jails, the 20 cells are usually arranged in straight rows or blocks and open into a common corridor or exercising space which is surrounded by what may be termed the jailer's corridor, separated from the prisoners' corridor by a 25 suitable construction of grating, so that the jailer may safely inspect all of the cells and control the movements of the prisoners without coming into direct contact with them.

30 Under ordinary conditions it may be safe to allow all of the prisoners to mingle in the same corridor for exercising during the day time, but in some instances it might be unsafe for the jailer to admit a new prisoner to the corridors while the others were confined therein, under which conditions the prisoners in the corridor may be forced to enter their respective cells after which their respective doors are locked before the cor-

40 ridor door is opened for the entrance of the new prisoner, the door of the cell for the latter being left open for his entrance. It therefore becomes necessary to provide means exterior to the cells and corridors 45 whereby the jailer may operate each cell door independently. On the other hand, in case of a riot or fire it is desirable to provide means whereby the doors of all the cells may be simultaneously closed or opened

50 to confine or release the prisoners according to the emergency. Again when the prisoners are locked in for the night, it is advisable to guard against malicious attempts to open the doors of the cells and for this purpose the sill or threshold of each door is 55 provided with a groove or channel and the

doors are hung upon a vertically movable support which is connected to a suitable operating member, whereby all of the doors may be simultaneously dropped into their 60 respective channels.

The main object is to provide means operable from a position at one end of the series of cells and exterior to the corridor, whereby the cell doors may be locked, released and operated individually or collectively and also to provide means operable from the same position for locking and releasing the corridor door.

Another object is to provide means whereby all of the doors may be simultaneously lowered and raised into and from a night lock, groove or recess in their respective sills or thresholds to enable the doors to be additionally locked at night independently of 70 the day locks.

Another object is to enable either one or all the doors to be partially opened and locked in such position when necessary as in supplying food or other articles to a 75 vicious prisoner without endangering the safety of the attendant.

Other objects and uses will be brought out in the following description.

In the drawings: Figure 1 is a front elevation of the first and last of a series of, in this instance eight, cell doors showing the mechanisms for locking, releasing and operating the same and also showing a portion of the mechanism for controlling the 90 operation of the corridor door, the adjacent portion of the cells being shown in elevation partly broken away, while the housings for the door operating and controlling mechanisms are shown in section. Fig. 2 95 is an end elevation of the door locking, releasing and operating mechanisms showing the corridor door in elevation and the locking box or housing in section. Fig. 3 is an enlarged side elevation of one of the cell 100 door operating mechanisms in position for opening the door, a portion of which is shown in elevation. Fig. 4 is an enlarged face view of one of the door hangers showing a portion of the door and also a portion 105 of the track together with the pawl for controlling the operation of the latch bars. Fig. 5 is an edge view partly in section of the parts shown in Fig. 4. Fig. 6 is a front elevation of one of the cell doors and supporting track therefor, showing the night lock operating mechanisms or means for 110

raising and lowering the track to drop or lift the door in and from the channel in the sill or threshold. Fig. 7 is a top plan partly broken away of the door controlling mechanisms showing the lock box and casing for such mechanism in section. Fig. 8 is an enlarged face view of the locking and releasing mechanism for the corridor door. Figs. 9 and 10 are sectional views taken respectively on lines 9—9, Fig. 2 and 10—10, Fig. 7. Figs. 11 and 12 are end views of the fixed locking disks and coöperating levers. Fig. 13 is an elevation of the corridor lock lever.

15 In illustrating the operation of my invention, I have shown in Fig. 1 the first and last of a series of, in this instance eight, sliding cell doors —1— of a corresponding number of cells, each door being supported 20 at its upper end by a pair of hangers —2— and rollers —3— upon a suitable track —4— which is common to all of the doors, the lower ends of the doors being guided and held against inward and outward movement 25 in suitable channels —5— in the sills or thresholds —6— of the cell doors.

The operating mechanism for the doors comprises a series of, in this instance eight, sprocket wheels —7— mounted coaxially, 30 side by side, upon a suitable supporting shaft —9— at one end of the series of cells and doors and also at the same end of the corridor, preferably in a line as nearly co-incident with the vertical plane of the doors 35 as may be possible in order that the connections between the sprocket wheels and their respective doors may be nearly in a direct line, the shaft —9— being disposed at substantially right angles to the cell doors. All 40 of these sprocket wheels except the last one of the series are mounted for independent rotary movement upon suitable interposed sleeves or collars —10—, the last one of the series being mounted directly upon the shaft 45 —9—, and are connected by sprocket chains —11— to independently movable door operating bars —12— which are preferably located some distance above the doors within 50 in a suitable housing —13— where they are connected in a manner hereinafter described to one of the hangers —2— of the corresponding door and are movable longitudinally in the direction of movement of said doors. These bars are of different lengths 55 corresponding to the distances of their respective doors from the end of the series at which the operating sprockets —7— are located.

The doors are normally locked in their 60 closed positions by one or more gravity latches or locking members —14— which engage in suitable keepers —15—, the latches of each door being disposed one above the other and movable vertically and are connected by a link-bar or rod —16— extend-

ing some distance above the door and terminating in a lateral offset or shoulder —17— for a purpose hereinafter described. The locking members —14— are preferably pivoted to a fixed portion of a door frame, 70 as —18—, while the link-bars or rods —16— are pivotally connected to the latches or locking members —14— between their pivots and the keepers —15—.

Each of the door operating bars —12— 75 is provided with a stud or laterally projecting pin —19— which rides in a furrowed end or open sided slot —20— in one arm of a bell-crank lever —21—, the latter being pivoted at —22— to one of the hangers —2— 80 of the door. The other arm of the bell-crank lever projects laterally in the direction of movement of the door and terminates in a cam face —23— normally riding under the shoulder —17— of the latch operating bar 85 —16—.

The sprocket wheels —7— and other mechanisms for controlling the locking, releasing and movement of the doors are enclosed within a suitable housing or lock 90 box —24— which is also located at the adjacent end of the series of cells outside of the corridor or within the usual passage assigned to the jailers and inspectors, so that the entire series of doors may be locked, released and operated individually or collectively by the attendant or jailer when outside of the prisoners' exercising corridor. The housings —13— and —24— communicate with each other at their adjacent ends 95 so as to provide for the reception of the sprocket chains and other parts of the door operating mechanisms connected to the sprockets —7—.

The opposite sides of each chain —11— 105 are passed upwardly and around suitable idlers —25— and —26— and then horizontally within the housing —13— around a suitable sprocket wheel —27—, said idlers —25— and —26— being journaled in suitable brackets —28— on the upper portions of a fixed upright supporting frame —29— while the sprocket —27— is similarly journaled in a bearing —30— within and supported upon the base of the housing —13—. 110 The opposite ends of each chain are connected to an anchorage —31— on the adjacent end of the corresponding door operating bar —12—, so that as any one of the sprocket wheels is rotated in the direction 115 indicated by arrow —x— from its normal position, it will impart longitudinal movement to the corresponding bar —12—, thereby rocking the bell-crank lever —21— between limiting stops —33—, thus engaging 120 the shoulder —17— and elevating the lock bar —16— and releasing the latches —14— from their keepers —15—, whereupon by the continued movement of the sprocket wheel and door operating bar —12— in the same 130

direction, the door will be opened from its normal closed position.

Each sprocket wheel is provided with a radially projecting hand lever —34— and pawl —35— which latter is located near the inner end of the lever and adapted to interlock with one or more notches —37— in the periphery of the adjacent spacing disk or collar —10—, the operation of said pawl being controlled by a link —38— and small lever —39— on the outer end of the main lever —34—.

The disks —10— which are coaxial and alternate with the sprocket wheels are keyed to the shaft —9— which in turn is normally held against rotation in the following manner.

A flange —40— is rigidly secured to a fixed bracket —41— within the housing —24—, the periphery of said flange being concentric with the axis of the shaft —9— and is provided with a series of notches —42— adapted to be engaged by a pawl —43— on a lever —44—. This lever —44— is also keyed to the shaft —9— and is provided near its outer end with a small hand lever —45— connected by a link —46— to the pawl —43— for operating the latter.

When the doors are in their closed positions, the levers —34— and —45— project downwardly and radially from the axis of the shaft —9— entirely within the housing —24— where they are concealed by a suitable door on the front side of the housing.

It is apparent upon reference to the foregoing description that when the levers are exposed by the opening of the door of the housing —24— any one of the doors may be opened by simply rocking the corresponding lever —34— forwardly and upwardly, the notches in the periphery of the disks —10— being located so as to permit the engagement of the pawl —35— therein to lock the door either in its closed or extreme open position, although in some instances I provide each disk with an additional intermediate notch, whereby the doors may be locked in a partially open position.

The lever —44— is for the purpose of operating all of the doors simultaneously and for this purpose it together with all of the disks is keyed to the shaft and it therefore follows that if the levers —34— are locked by their respective pawls to the disks —10—, the forward and upward rotation of the lever —44— will rotate the entire series of sprocket wheels —7— together with the disks —10— and corresponding operating levers —34— to impart corresponding movement to the bars —12— and cell doors connected thereto, the fixed flange —40— being provided with notches corresponding to those in the disks —10— to coöperate with the pawl —43— for locking the doors collectively in their extreme open or closed

position or in an intermediate open position.

When the cell doors are closed and locked to confine the prisoners for the night, it is preferable to provide some means for dropping the doors into their respective channels, so as to additionally lock them against any malicious effort to force them open and for this purpose I provide an additional lever —48— which is loosely journaled on the outer end of the shaft —9— and is eccentrically connected by a link —49— to a crank arm —50—. This crank arm —50— is journaled in a suitable bearing —51— on one side of the lock box —24— and is connected by an additional crank arm —52— and link —53— to one end of the track —4—. The track —4— is pivotally mounted for parallel longitudinal movement upon a plurality of crank arms —55— which in turn are journaled at their lower ends below the track in suitable brackets —56— within the housing —13—, so that as the lever —48— is rocked to and from its normal position longitudinal and vertical movement will be imparted to the track, thereby permitting the doors to drop into their respective channels when the lever is elevated to the position shown in Fig. 6.

As best seen in Fig. 2, the end of the corridor nearest the locking box —24— is provided with a hinged door —57— similar in construction to the cell doors and adapted to be locked and released by mechanism located within the lock box —24—. For this purpose the free side of the door swings in close proximity to the adjacent side of the lock box and is provided with one or more keepers —58— for the reception of slideable locking bolts —59— which extend transversely and are guided in bearings —60— on the back of the lock box.

A vertically movable bar —61— is guided in suitable ways —62— on the opposite side of the lock box —24— and is provided with laterally projecting abutments —63— which normally lie close to and in the path of the adjacent ends of the locking bars —59— to prevent said locking bars from being unlocked from the keepers —58—, except when the vertically sliding bar —61— is shifted by the jailer or other attendant.

The means for operating the bar —61— preferably consists of a lever —65— pivoted to the adjacent side of the box —24— and pivotally connected at —66— to the bar —61—, so that by depressing the outer end of the lever —65—, the bar —61— will be elevated to shift the abutment —63— out of registration with the adjacent end of the locking bolts —59—. These abutments —63— are also utilized to engage one of the arms of bell-crank levers —67— which are pivoted at —68— to one side of the housing —24—, while their other arms are pivoted

to their respective locking bolts —59—, as clearly shown in Fig. 2.

The arms —67— are disposed in a substantially horizontal position in the path of movement of the respective abutments —63— with just sufficient clearance between them to permit said abutments to be withdrawn from the path of movement of the locking bolts —59— before engaging said horizontal arms and by the continued upward movement of the bar —61—, by means of the lever —65—, these abutments —63— engage the overlying portions of the bell-crank lever —67— thereby rocking them to draw or interlock the bolts —59— from the keepers —58—.

When the lever —65— and bar —61— are returned to their normal positions, the bell-crank levers also return by their own gravity and force the bolts —59— to their locking positions.

The doors are prevented from upward displacement from the track —4— by rollers —69— which are journaled in the hangers —2— just below the lower edge of the track and directly opposite the rollers —3—, thereby preventing the doors from being pried or forced upwardly, as best seen in Fig. 5.

30 The operation briefly described is as follows:—When it is desired to open anyone of the doors independently of the others, the jailer engages the corresponding lever —34— and releases its pawl —35— from engagement with the adjacent disk —10— and then rocks said lever forwardly and upwardly, thereby rotating the corresponding drum —7— and transmitting longitudinal motion to the bar through the medium of the chain —11—. By these means either cell door may be slightly opened just sufficient to insert the hand or food dishes and locked in such position, or such door may be opened and locked in its extreme open position, or by the reverse movement of either of the levers —34— the corresponding door may be closed and automatically locked by the catches —14— and also by means of the pawls —35— entering their corresponding notches —37—. In like manner all of the cell doors may be operated simultaneously and locked in their parallelly open or extreme open position by means of the lever —44— and pawl —43— coöperating with the notches —42— in the disk —40—.

When the cell doors are moved to their extreme closed positions, the supporting track —4— may be lowered by the operation of the lever —48— to drop the lower ends of the doors into the channels —5— to further lock the doors against being forced open, particularly at night.

60 The corridor door —57— is hinged as distinguished from the sliding cell doors and is

locked and released by the locking bolts —59— which are located in the locking box and are operated by the lever —65— through the medium of the bar —61— and bell-crank levers —67—.

70 It will be observed upon reference to the foregoing description and accompanying drawings that when the door supporting track is dropped or lowered to drop the doors into their respective channels the bars —16— which connect the pivoted latches —14— also drop by their own gravity to keep the latches —14— in locking engagement with their respective keepers —15—.

75 What I claim is:

1. In an apparatus of the class described, in combination with a plurality of doors, a rock shaft, means for rocking the shaft, disks, one for each door secured to the shaft, door-operating members journaled on the disks, separate connections between said members and their respective doors, and separate devices for locking and releasing said members to and from their respective disks whereby the doors may be operated 80 simultaneously, individually or in groups of two or more.

2. In door operating and locking mechanism for jails, in combination with a plurality of doors, a rock shaft, a plurality of rotary coaxial members concentric with and rotatable independently about the axis of the shaft and each provided with a separate operating lever rigidly secured thereto, separate connections between said rotary members and doors, separate devices for locking each of said levers to the shaft, and means for rocking said shaft and thereby operating all of the levers which may be locked to the shaft.

3. In door operating and locking mechanism for jails, in combination with a sliding door, a rock shaft, a collar secured to the rock shaft and provided with notches in its periphery, a rotary member coaxial with and movable relatively to said collar and provided with a pawl movable into and out of engagement with said notches for locking and unlocking the rotary member to and from the collar, connections between said rotary member and door for imparting sliding motion to the latter by the rotation of said member, means for rotating said member when unlocked from the collar, and separate means for rotating the shaft when the rotary member is locked to or unlocked from the collar.

4. In door operating and locking mechanism for jails, in combination with a sliding door, a lock therefor, a supporting track 125 for the door, a lock releasing bolt, a bolt operating member pivotally mounted upon the door, and means operatively connected to the bolt operating member for releasing the bolt and opening the door.

5. In combination with a sliding door, operating means therefor comprising an endless cable and supporting drums therefor, a lever secured to one of the drums for rotating the same to operate the cable, connections between one side of the cable and door for transmitting motion to said door, a relatively stationary disk coaxial with the lever operated drum and provided with notches in 10 its periphery, and a pawl on the lever operated drum for engaging in the notches of the disk.

6. In combination with a plurality of sliding doors arranged in sequence and movable 15 vertically, a supporting track for the doors, rock arms supporting the track, separate devices for operating the doors individually along the track, additional means for operating all of said devices simultaneously 20 along said track, and further means for moving the track endwise upon its rocking supports to raise and lower the doors.

7. In combination with a plurality of sliding doors arranged in sequence, operating 25 means therefor comprising a rock shaft, disks, one for each door, keyed to the shaft, individual door-operating members coaxial with and rotatable relatively to the disks, separate devices for locking the individual 30 door-operating devices to the disks whereby said devices will be locked to the shaft, and means for rotating said shaft to move all of the doors simultaneously.

8. In combination with a sliding door, a 35 supporting track for the door, a rocking support for the track, a lever, connections between the lever and track for shifting the track endwise and thereby rocking its supports to raise and lower the track and door 40 mounted thereon.

9. In combination with a sliding door, a door frame, a lock box at one edge of the door, operating means for the door comprising an endless cable having a portion there- 45 of arranged in the lock box and mounted upon the drum therein and its upper portion extending horizontally above the top of the door and engaged with the drum on the door frame above the door, a relatively 50 stationary locking member in the lock box coaxial with the drum therein, means in the named drum movable into and out of engagement with said locking member for locking the drum against movement and connections between the upper horizontal portion of the cable and door for transmitting motion to the door when the drum is operated.

10. In combination with a lock box, a series of sliding doors arranged in sequence 60 from the lock box, a vertically movable supporting track for the doors, rocking supports for the track, and means located in the lock box for moving the track endwise and thereby rocking its supports to raise and

lower the track and simultaneously raise and lower the doors mounted thereon.

11. In combination with rocking supports and a track pivoted thereto, a plurality of doors arranged in sequence and movable 70 along said track, separate operating devices for said doors, and means for moving the track endwise and thereby rocking its supports to raise and lower the track and doors mounted thereon. 75

12. In combination with a sliding door and a supporting track therefor, a cable, supporting drums for the cable, connections between the cable and door including a bar movable a limited distance independently of 80 the doors, a lever connected to the bar, means for limiting the movement of the lever and thereby limiting the movement of the bar, means for rotating one of the drums, means for locking the door in its 85 closed position, and additional means actuated by the limited movement of the lever to release the locking means prior to the opening of the door.

13. In combination with a sliding door, a 90 supporting track for the door, hangers connected to the door and resting on the track, locking members for the door, a bar connecting the locking members, a lever on the door for engaging and operating said bar to release the locking members, means for limiting the movement of the lever, a bar operatively connected to the lever and movable 95 independently of the door, a cable connected to the bar, supporting drums for the cable, 100 means for rotating one of the drums, and additional means for locking such drum in different positions to hold the door in its adjusted position.

14. In an apparatus of the character de- 105 scribed, a sliding door, an overhead supporting track for the door, a guide-channel for the bottom of the door, rock arms supporting the track and pivoted thereto to move in the direction of its length, and means for 110 moving the track endwise to rock said arms and thereby raise and lower the track and door supported thereby relatively to the guide-channel.

15. In an apparatus of the character de- 115 scribed, a sliding door, an overhead support- ing track for the door movable longitudinally, a guide-channel for the bottom of the door, means for moving the track endwise, and additional means for raising and low- 120 ering the track as it is moved endwise where- by the door is correspondingly raised or low- ered relatively to the guide-channel.

16. In an apparatus of the character de- 125 scribed, a sliding door, an overhead track for the door, a guide for the bottom of the door, means for moving the track endwise, additional means to cause the track to raise and lower as it is moved endwise for raising and lowering the door relatively to the guide, 130

and additional means for locking the track-operating means in its adjusted position for holding the door either in its raised or lowered position.

5 17. In an apparatus of the character described, a sliding door, a guide for the bottom of the door, an overhead supporting track for the door, rock arms pivoted to and supporting the track, means including a hand lever for moving the track endwise and thereby rocking its supporting arms to raise and lower the track and door relatively to the bottom guide, and separate means for moving the door along the track.

10 18. In an apparatus of the character described, a sliding door, a guide for the bottom of the door, an overhead track supporting the door and having a limited endwise movement, means for raising and lowering the track and door as it is moved endwise in reverse directions, a crank arm, connections between said crank arm and track for moving it endwise, a hand lever, connections between the hand lever and crank arm for operating said crank arm, and means for locking the lever against movement to prevent endwise movement of the track.

15 19. In an apparatus of the character described, a sliding door, a supporting track for the door, a locking member for said door, a vertically movable bar connected to the locking member for operating the same, means for moving the door along the track to open and close the same, said means including a lever fulcrumed on the door and operated by the door-opening means for engaging and lifting the bar to release the locking member from its locking position before the door begins to open.

20 20. In an apparatus of the character described, a sliding door, a bar movable in the direction of movement of the door, a lever mounted on the door and having a limited movement relatively thereto, said lever being connected to the bar for transmitting motion therefrom to the door, means for operating

the bar to open and close the door, a locking device for holding the door in its closed position, and means actuated by the limited movement of the lever relatively to the door 50 for tripping the locking device and releasing the door during the initial movement of the door-operating means.

21. In an apparatus of the character described, a sliding door, a supporting track 55 therefor, a bar movable in the direction of movement of the door, connections for transmitting motion from the bar to the door including a bell crank lever pivoted to the door and having a limited movement relatively 60 thereto, means on the door for limiting the movement of the bell-crank lever, and means for operating the bar to open and close the door, a locking member for holding the door in its closed position, a vertically movable 65 bar connected to the locking member, and means on the bell-crank lever for engaging and lifting the lock-operating bar for releasing the lock during the initial movement of the door-operating bar.

22. In an apparatus of the character described, a plurality of doors and operating means therefor comprising a rock shaft, means for rocking the shaft, separate rocking members coaxial with the shaft and movable relatively thereto, separate devices for rocking said members, separate connections between said members and the doors for opening and closing the same individually, and separate devices for locking said members to the rock shaft whereby those which are locked to said shaft may be operated simultaneously by the shaft-operating means to open or close the corresponding doors collectively.

In witness whereof I have hereunto set my hand on this 14th day of October, 1910.

JAMES A. LOYSTER.
